but as my mechanism for some of those purposes is especially useful and novel I make subsidiary claims for combinations of certain portions of it.

5 As is manifestly evident from the description of the machine and its mode of operation, the essential feature is some device or combination of devices by which the weft-threads (which extend from each side of the 10 fabric to near the center thereof and back again) may be interlocked one with the other. This feature is absolutely necessary, as without it the harness could not be produced, and the devices employed by me to accomplish 15 this result are the basis of the invention herein described. One weft-thread must be carried about the other. Of course this might be done in various ways; but my way seems especially simple and effective—to wit, to place the 20 thread carrier or holder (here the shuttle) upon a support capable of rotary movement, then rotate that support (disk J) in such a manner that one thread-holder crosses the path of the other thread and the ends of 25 the respective threads are passed under the opposite threads, whereby they are interlocked, at the same time preferably interposing (within the orbit of the thread-holder) a pin, upon which the loops may be properly 30 sustained while the operation is performed, so that the thread-carrier supported between the warps on each side, (here upon a disk,) the support, and mechanism for rotating it not only in fact constitute the heart, as it 35 were, of the machine shown, but the devising and arranging thereof in their present relations constitutes as well the heart of the invention which I desire to secure, as it renders unnecessary a cumbersome system of gears 40 which are more expensive, less effective, and more liable to get out of order.

What I do claim as my invention, and desire to secure by Letters Patent, is—

1. A disk mounted to rotate in a loom and 45 carrying portions of two shuttle-races, in combination with a pin projecting beyond the surface of said disk, and mechanism, substantially as described, whereby said disk is rotated, substantially as and for the purpose 50 specified.

2. A disk mounted to rotate in a loom and carrying portions of two shuttle-races, in combination with two pins *h h*, mechanism, substantially as described, whereby said pins are 55 respectively alternately projected and retracted, and mechanism, substantially as described, whereby said disk is rotated, substantially as and for the purpose specified.

3. The combination, in a loom, of two weft- 60 thread holders, a shaft mounted to rotate in said loom, a support secured to said shaft and carrying the thread-holders so that they rotate with said shaft, the orbit of each thread-holder passing across a line drawn from the 65 opposite warp to the position occupied by the

other thread-holder at some period of the rotation, and mechanism, substantially as described, for rotating said shaft, support, and holders, as and for the purpose set forth.

4. The combination, in a loom, of two weft- 70 thread holders, a shaft mounted to rotate in said loom, a support secured to said shaft and carrying the thread-holders so that they rotate with said shaft, the orbit of each thread-holder passing across a line drawn from the 75 opposite warp to the position occupied by the other thread-holder at some period of the rotation, a pinion connected to said shaft and provided with a foot, a gear provided with a toothed segment, and mechanism for rotating 80 said gear, substantially as set forth.

5. The combination, in a loom, of two weft- 85 thread holders, a shaft mounted to rotate in said loom and carrying means for supporting said thread-holders, and mechanism, substantially as described, for rotating said shaft and holders, as and for the purpose stated.

6. A disk mounted to rotate in a loom and carrying portions of two shuttle-races, in combination with mechanism for rotating said 90 disk, all substantially as set forth.

7. A disk mounted to rotate in a loom and carrying portions of two shuttle-races, a pinion connected to said disk and provided with a foot, a gear provided with a toothed segment arranged, as described, to mesh with 95 said pinion, and mechanism for rotating said gear, substantially as set forth.

8. The combination of a disk carrying portions of two shuttle-races, a pinion connected 100 to said disk and provided with a foot, means for moving said pinion laterally, a gear provided with a toothed segment into and out of position for engagement with which said pinion is thrown when moved laterally, and 105 mechanism for rotating said gear, all arranged and combined substantially as set forth.

9. A disk mounted to rotate in a loom and carrying portions of two shuttle-races, in combination with mechanism for rotating said 110 disk, two shuttle-races, two shuttles, and mechanism for driving the same, all combined substantially as set forth.

10. A disk mounted to rotate in a loom and carrying portions of two shuttle-races, in combination with mechanism for rotating said 115 disk, two shuttle-races, two shuttles and mechanism for driving the same, and packers and means for driving them, all substantially as set forth.

11. A disk mounted to rotate in a loom and carrying portions of two shuttle-races, in combination with mechanism for rotating said disk, two shuttle-races, two shuttles and mechanism for driving the same, and packers 125 and means for driving them, and a pin extending between the positions occupied by the shuttles on said disk, all substantially as set forth.

12. A disk mounted to rotate in a loom and 130
